Primary Examiner — Brett Miller*Assistant Examiner* — Rani J Abdallah(57) **CLAIM**

The ornamental design for a portion of a liquid container, as shown and described.

DESCRIPTION

FIG. 1 is a perspective view of a portion of a liquid container of the present invention;

FIG. 2 is a left side view thereof;

FIG. 3 is a front view thereof;

FIG. 4 is a back view thereof;

FIG. 5 is a top view thereof; and,

FIG. 6 is a bottom view thereof.

The broken lines are for illustrative purposes only and form no part of the claimed design.
